ATTORNEY.

UNITED STATES PATENT OFFICE.

HENRY ORSENIGO, OF MOUNT VERNON, NEW YORK.

DESIGN FOR A CABINET FOR A PLAYER PIANO OR THE LIKE.

Application filed August 18, 1923. Serial No. 7,033. Term of patent 3½ years.

To all whom it may concern:

Be it known that I, HENRY ORSENIGO, a citizen of the United States, residing at Mount Vernon, county of Westchester, State of New York, have invented a new, original, and ornamental Design for Cabinets for Player Pianos or the like, of which the following is a specification, reference being had to the accompanying drawing, forming part thereof.

The figure is a perspective view of a cabinet for player pianos and the like, showing my new design.

I claim:

The ornamental design for a cabinet for a player piano or the like, as shown.

HENRY ORSENIGO.

Witness:

THOMAS DAVIES.
